EVAPORATIVE COOLING SYSTEM FOR A
HUMIDIFIED INCLOSUREAlbert J. Loepsinger, Providence, R. I., assignor to
General Fire Extinguisher Company, Providence, R. I., a corporation of Delaware

Application August 19, 1938, Serial No. 225,779

7 Claims. (Cl. 98—33)

This invention relates to an improved evaporative cooling system for a humidified inclosure. In my co-pending application, Serial No. 15,811 filed April 11, 1935 and allowed July 14, 1938, and now Patent No. 2,128,096, August 23, 1938 I have disclosed apparatus for controlling the cooling of such an inclosure and this application is a continuation in part of that former application.

The present invention is directed to the cooling of an inclosure in which the humidifying means are distributed throughout the inclosure and, under suitable control, discharge moisture directly into the atmosphere of the room. Thus this invention is distinguished from what is commonly known as a "central station system" in which the air forced into the inclosure is pre-humidified before being admitted to the atmosphere of the room.

In the textile field particularly, the maintenance of a desired humidity condition of the air in a room or inclosure where the processing of textile material is being carried on has long been recognized as essential. Various means have been developed and used for supplying moisture to the air, the commonest and most effective being the atomization of water into extremely small particles resembling a fog which is blown into the atmosphere of the inclosure. The capacity of each humidifying unit is relatively small, and a considerable number of such units are scattered throughout the space to be moistened. On being discharged into the air the small droplets of water composing the fog are evaporated. As this evaporation involves a change of physical state from a liquid to a vapor, the latent heat required is withdrawn from the surrounding air. Humidification alone thus inherently also causes cooling to an extent depending upon the amount of latent heat withdrawn by evaporation.

Where the percentage of relative humidity is to be maintained within a desired range, or at some predetermined per cent with allowable slight tolerances therefrom, it is obvious that the cooling by evaporation must be secondary to the maintenance of the desired humidity condition. If the evaporation becomes so excessive that the desired relative humidity is exceeded, the humidifying means are rendered inactive by suitable control apparatus responsive solely to the humidity. If, on the other hand, the air changes are so frequent as to overtax the capacity of the humidifying means, the amount of fresh air admitted to the inclosure must be reduced, so that in any event the desired humidity condition shall

be promptly restored and maintained regardless of the temperature.

Perhaps the most difficult conditions encountered are those pertaining when the outside air is at moderate temperature and its relative humidity is high. Under such conditions a large volume of outside air must be admitted and the changes of air must occur frequently. In certain textile rooms, for example, in a spinning room where the considerable horse power required may be deemed to be almost entirely converted into heat, causing unbearably high temperatures if not dissipated or absorbed by some cooling process, air changes of the order of from fifteen to twenty times an hour are required to produce the desired cooling effect. The introduction of this large amount of untreated outside air, in such a way as not to upset the desired condition of relative humidity for the material being processed is not easily accomplished.

The haphazard air changes obtained from opening windows, while helpful, cannot supply enough air to depress the temperature as much as is possible by evaporative cooling. The most successful attempts at controlled air changes have been made heretofore with the use of large graduated ducts ramifying about the inclosure and designed to discharge air into the atmosphere through many small outlets. While the small amount of air introduced from each such outlet can be readily moistened by nearby humidifying means, there are nevertheless serious practical objections to a duct system.

As already pointed out, the amount of air to be handled is large, and the ducts must be large also to keep velocities and friction loss within the limits set by good engineering practice. Such a system is expensive to fabricate and install, and even when well designed necessitates a large fan which requires considerable power to drive it. The dimensions involved make the duct a serious obstruction to the lighting system, and decrease the effectiveness of the automatic sprinklers by interfering with distribution of water discharge from them when a fire occurs. The disposal of lint and fly in textile mills is a troublesome problem which is further complicated by the presence of a duct system. Accumulation on the top of the ducts is rapid, and must frequently be removed, often necessitating shutting down and covering machines in the vicinity. The ducts are so arranged at the intake end that on occasion air from the inclosure is mixed with outside air and sometimes the air from the inclosure alone is recirculated. Under these cir-

cumstances deposits of lint and fly accumulate inside the ducts where removal is difficult and, moreover, constitute fire hazards.

One of the objects of my invention is to eliminate the use of ducts and to provide a ductless system utilizing portions of the normal openings in the inclosure for the admission of large quantities of outside air. Another object is to provide for the immediate mixing with the outside air of a greater or lesser proportion of the room air before the mixture is propelled into the room. And another and important object is to cause this mixture of primarily untreated air to be distributed in what I term the upper stratum of the inclosure so as to be generally available to all the humidifying units distributed about the inclosure.

In the case of a room where manufacturing is going on, the machinery and the operatives 20 are in a stratum near the floor. In other rooms used for the humidity conditioning of goods, the latter are usually in a similar lower stratum. It is the atmosphere of this stratum which must be maintained at the desired relative humidity 25 for the best processing of the material. Likewise where operatives and machinery are employed, it is this stratum which must be cooled because into it are liberated the heat units from the machinery which materially tend to increase the 30 temperature near the operatives. Customarily the humidifying apparatus is arranged above this lower stratum. Whether the units be humidifying heads or atomizing nozzles, or both, they are usually arranged to discharge the moisture into 35 what I shall term an intermediate stratum.

The stratum above the humidifying means has heretofore for the most part been neglected and not usefully employed in respect to air conditioning. Where forced air changes have not 40 been provided, the air in this upper stratum has been relatively quiescent or stagnant. Even with duct systems, there is no attempt made to utilize the upper stratum as a whole for a sort of reservoir of untreated air generally available for all 45 the humidifying means, or to bring about any one uniform movement of air throughout the upper stratum. It is a feature of my improved system to make definite use of this upper stratum and to so arrange the inlet and outlet openings 50 that the air propelled into this upper stratum will traverse the entire inclosure.

The most economical way of moving large quantities of air against low resistance is by means of the propeller type fan. In employing 55 such fans I preferably place them at inlet openings in certain walls of the inclosure with vents for exit remotely located from the inlets. Thus the air propelled by the fans must traverse the inclosure. Since the area available for intake is, 60 however, limited, and since a large number of air changes are to be provided, the volume introduced at each opening must be great. It is a feature of the present invention to introduce this large amount of air in a concentrated area in 65 such manner as to preserve the desired percentage of relative humidity in the lower stratum of the inclosure. This is accomplished by utilizing the upper stratum for the distribution of the air propelled by the fans. To that end I place the 70 inlet apparatus, and, when necessary, provide directional vanes, so that the large volume of incoming air will be directed into the upper stratum above the humidifying apparatus.

There are thus present the three strata before 75 mentioned, a stratum above the humidifying ap-

paratus comprising air which may be said to be deficient in humidity, next below is the stratum in which the humidifying means are located and in which the air is nearly saturated or exceedingly high in humidity, and below that is the lower stratum in which the air is to be maintained at a desired relative humidity and cooled to as comfortable a temperature as can be attained by evaporative cooling. As the air leaves an inlet it travels through the upper stratum in a well defined jet, which, as it travels farther, spreads and loses velocity. This is true even where the location of a window may require the inlet opening to be rather low, in which case, the air leaving the inlet is directed upward and into the upper stratum and thus does not depress the relative humidity in the lower stratum adjacent the inlet wall. Because of this jetlike action and the slight pressure created by the fans there is throughout the upper stratum a constant movement of air away from the fans towards the exit openings. The humidifying apparatus in the stratum below withdraws this fresh air either by direct fan action in the case of humidifying heads or by induced action in the case of atomizers. In the humidifying stratum the air near to the humidifying means is brought to a percentage of relative humidity much higher than that desired in the lower stratum, some of it being saturated. During this process rapid cooling 30 takes place so that the super-humidified air sinks downward into the lower stratum where it is mixed with air at a higher temperature and lower relative humidity to produce the percentage desired. There is thus in the lower stratum an up and down circulation, together with a gradual movement of the air as a whole towards the exit openings. Air in that portion of the lower stratum near to the fans is satisfactorily circulated by air currents induced by the rapidly moving incoming jets above.

A feature of my improved system in connection with the use of propeller fans is the provision for mixing room air with outside air at the inlets. Air changes are required almost throughout the 45 year so that in certain seasons if the temperature of the outside air falls below the dew point of the air inside, condensation will occur as soon as the cold outside air mixes with the room air. This would appear as a long jet of rather heavy 50 fog issuing from the fans, a condition intolerable because the free moisture in this cold jet would precipitate onto the machinery and work before it could evaporate. My system takes care of that difficulty by providing a thermostatic 55 control which can be set to insure that the mixture of outside air and inside air will always be above the dew point of the latter.

Other important features which characterize my improved system are the movement of a large 60 volume of air at high velocity by the inlet apparatus, and the discharging of it directly into the atmosphere of the inclosure. Where the inlet apparatus can be located high enough in a window or other normal opening in a wall, the fan 65 itself can be depended upon for the directional control of the flow into the upper stratum, but if such normal opening is lower than desired, directional vanes are to be employed to insure that the air propelled by the fan shall be promptly directed toward the ceiling and thus into the upper stratum. There is thus set up a rather definite directed movement of the fresh air in the uppermost stratum and because of this the air does not reach the lower stratum until it has been 75

moistened. The humidifying means, as before pointed out, draw air from the uppermost stratum, very nearly saturate it and discharge this highly humidified air into the middle or intermediate stratum. This highly humidified air thereupon floats downward into the lowermost stratum because of the natural up-and-down movement of the air between the lower and intermediate strata occasioned by their differences in 10 temperature.

The discharge outlets for air from an inclosure served by my improved system may be variously arranged, provided only that they lend themselves to the primary scheme of directional movement of the air through the several strata and in traversing the inclosure. Ordinarily, the discharge outlets or exit means would preferably be arranged in some wall of the inclosure other than that in which the openings for the incoming 20 air are provided but may be located when convenient in a monitor or otherwise in the roof of a building.

The best mode in which I have contemplated applying the principles of my invention are shown in the accompanying drawing but these are to be taken as merely illustrative because it is intended that the patent shall cover by suitable expression in the appended claims whatever features of patentable novelty exist in the invention as a whole.

In the accompanying drawing the single figure is a cross-sectional elevation of a humidified inclosure with provision for evaporative cooling in accordance with the present invention.

Referring more particularly to the drawing, there is shown a humidified inclosure having a floor 1, outside walls 2 and 3, and a ceiling 4, all of which is representative of a room in a textile mill or any inclosed space wherein it is desired 40 to maintain a predetermined humidified condition of the atmosphere in the lower stratum and to keep the temperature thereof as comfortable as possible. Humidifying means are provided for introducing moisture into the atmosphere of the inclosure, such means being indicated by humidifying head 5 and atomizing nozzle 6, either or both of which may be employed.

The humidifying head 5 here shown has a vertical casing 7 with a fan 8 near its top opening which runs continuously drawing air inward and forcing it downward through the casing and outward into the atmosphere through a horizontal circular nozzle 9. Within the vertical casing is provided the usual water spray jet through 55 which the air is forced to pick up and entrain globules of water. The humidifying action of such a head is controlled by the shutting off or turning on of the water by means of a valve 10 which, as here shown, is actuated by compressed air. The latter is received via a supply pipe 11, which leads to any suitable control unit 12 from whence another air pipe 13 leads to the valve 10.

The atomizing nozzle 6 is mounted on an air line 14 in which is a control valve 15 connected to pipe 13 so that when the compressed air is made available by the control unit 12 to open the water valve 10 and permit flow of water to the humidifying heads, the same air pressure will be effective to open valve 15 and supply compressed air in the line 14 to cause an atomized discharge of water through the atomizing nozzle, which is also connected to a water pipe 16.

The humidifying means, whether of the head or nozzle type, or both, are located at a level 75 above the stratum where the operatives are at

work and the machines and material in process are located or stored. The air leaving the heads or the nozzles is well nigh saturated and thus there is established in the inclosure an intermediate horizontal stratum wherein the air thereof is highly moistened. To provide the desired humidity condition in the lower stratum, this highly moistened air must mix with the air in the lower stratum. This ordinarily presents no problem because the highly humidified air is 10 at about the temperature of saturation and falls to the lower stratum. Thus the mere object of maintaining a desired humidity condition for the processing of the material has readily been attained without difficulty for many years past. 15

But the mere maintenance of a desired humidity condition is not enough. It is equally desirous that the temperature of the lower stratum be kept at a comfortable degree. As has been hereinbefore pointed out when the temperature is to be controlled by evaporative cooling, there must be frequent changes of the air so that the moisture can be readily and continuously evaporated. In short, as the air in the lower stratum becomes humidified to the desired limit 20 of relative humidity, having thereby absorbed all the moisture it should and thus having provided the full cooling effect possible consistent with the maintenance of the desired humidity condition, this air should move on, as it were, and be replaced by new air capable of continuing the evaporative process for the cooling influence. This involves the admission of fresh and relatively unhumidified air to the inclosure, and the particular problem becomes one of proper distribution of this fresh air and the movement of 25 all the air in the inclosure to maintain the condition of the air in the lower stratum as nearly uniform as possible.

My improved system accomplishes this in the 40 following manner. In an ordinary opening of the room, such as a window 17 in the outside wall 2, there is arranged a casing 18 in which is suitably mounted a fan 19 and its driving motor 20. This casing has two entrances 21 and 22. 45 The entrance 21 is at the side exposed to the outside air and the other entrance 22 is at the bottom exposed to the air within the inclosure. These entrances or inlet openings are each provided with a series of interconnected louvers 23, 50 24 so arranged that as the outside louvers 23 are opened the inside louvers 24 are closed and vice versa. Thus as air is drawn through the inlet entrances 21 and 22 by the fan 19, the proportion of fresh outside air to the air taken from within the inclosure may be regulated as desired. For example, a common modulating thermostatic device 25 can be arranged in the path of the air flow from the fan and be connected to a motor 26 so as to control the settings of the louvers 23, 55 24 to give a proportionate mixture of outside and inside air. It is important that this mixture, or the air propelled by the fan 19 shall have a temperature above the dew point of the room air. This will prevent any formation of fog or precipitation of moisture which might occur if the temperature of the outside air should fall below the dew point of the inside air.

The casing 18 is located as near the top of the window or side wall of the closure as is possible 70 and its discharge opening 27 is provided with a series of directing louvers 28 which, while adjustable to determine their position, are normally set to direct the fan driven air very definitely upward toward the ceiling. 75

The volume of air moved by a fan 19 is large and its velocity is relatively high, so that when initially directed upward toward the ceiling it tends to continue to flow along the upper stratum of the air substantially across the inclosure above the humidifying means. Of course, this initially rapidly moving current of air from the fan spreads out after it leaves the casing 18 and because of this, and the normal frictional resistance encountered by the air, the velocity of the air naturally tends to diminish. However, it is to be understood that both the initial volume and velocity must be sufficient, together with the slight pressure created, to insure that the air propelled by the fan will move in the upper strata in a general direction toward a vent opening 29.

In the region of the lower stratum close by the inlet wall 2, there is no "dead-space" because when the louvers 24 are opened at all, a flow of air from the lower stratum is induced by the general flow into the opening 22. And even when the latter is closed, the rapidly moving air discharged from the casing 18 sets up an induced flow from the lower stratum generally upward along the inside of wall 2.

Although for purposes of illustration I have only shown one inlet opening, one outlet opening, and one of each of the characteristic humidifying means, it is to be understood that the latter are distributed throughout the inclosure and that additional inlet and outlet openings will be provided as needed.

The purpose of the directed air movement in the upper stratum is to make available to the humidifying means a source of relatively unhumidified air or air deficient in humidity, which can be induced to flow into the heads 5 or into the induced currents formed by the nozzles 6, and continuously pick up and entrain the moisture. As the air becomes moistened in the intermediate stratum of highly humidified air it moves downward into the lower stratum. In the latter there is a continual movement of the air due to several causes. One has already been noted being the movement of the moistened air downward due to its low temperature, and the movement upward of this air after it has been heated in the lower stratum. Another influence is the intake of air into the casing 18 when the louvers 24 are opened to any degree. And finally there is the general flow of the air toward the outlet openings 28.

Where the inclosure being conditioned has opposite outside walls, it is highly desirable that the outlet openings for discharge of the room air be in the wall opposite that through which the fresh air is admitted. This preferred arrangement is seen in the figure where the outlet or discharge opening 28 is shown at the top of window 30 in wall 3. This particular location of the exit means is preferred because it is at the end, or possibly beyond the end, of the directed movement of the air in the upper stratum. Being at the top of the window any localized drafts set up by the outgoing flow are not felt by the operatives working near the wall 3 in the lower stratum of the air. There is merely a sort of lazy travel or movement of the air more or less horizontally along the lower stratum with a gradual turning upward and outward as the moving air approaches the wall 3. Where, however, it is not possible or convenient to locate the exit openings in an opposite wall they may be provided at any remote location from the inlet favorable to the general directional travel of the air above mentioned.

While I have heretofore mentioned that the settings of the louvers 23 and 24 of the inlet casing 18 can be controlled by a modulating thermostat 25, it is also to be understood that any other suitable control means may be used. For example the motor 26 connected to the louvers 23, 24 might be actuated by a control unit 31 in response to either or both the humidity or temperature conditions of the room air, and be effective to vary the setting of the louvers. Moreover, in the event that it is desired to prevent any entry of outside air when the temperature within the inclosure reaches some predetermined minimum degree, a thermostatic device 32 may be provided which assumes control upon such temperature being reached and effects the closure of the louvers 23 so long as the temperature in the lower stratum is at or below the permissible minimum.

By my improved method of directing the flow of an appreciable volume of air admitted from the outside, or a mixture of outside air with the inside air of an inclosure, and providing for a generally directed movement of this air through the upper stratum, a likewise generally directed induced flow of this air into a stratum of highly humidified air, and a further generally directed flow of the highly humidified air into the lower stratum, a substantially uniform condition of desired relative humidity and comfortable temperature is maintained. And, to repeat, this substantially uniform distribution of humidity in the lower stratum and the desired comfortable temperature thereof is effected by my improved system without using any ducts whatever.

I claim:

1. An evaporative cooling system for a humidified inclosure having a lower stratum to be cooled and maintained at a desired relative humidity; humidifying means distributed about the inclosure in an intermediate stratum above said lower stratum; means adjacent a wall for drawing in outside air and propelling it directly into the atmosphere of the inclosure in an upper stratum above said intermediate stratum in sufficient quantity and with sufficient velocity to be substantially uniformly available to the humidifying means distributed about the intermediate stratum; and exit means for discharge of air from the inclosure located remote from said air propelling means; the said humidifying means acting to move air from said upper stratum into said intermediate stratum and there to highly humidify and cool the air, whereby said highly humidified and cooled air descends from the intermediate stratum into the lower stratum and reduces the temperature of and establishes the desired condition of relative humidity in the air of said lower stratum, there being a general movement of air throughout the inclosure from said air propelling means to said remote exit means.

2. An evaporative cooling system for a humidified inclosure having a lower stratum to be cooled and maintained at a desired relative humidity; humidifying means distributed about the inclosure in an intermediate stratum above said lower stratum; means for propelling air directly into the atmosphere of the inclosure in an upper stratum above said intermediate stratum comprising a casing adjacent a wall of the inclosure having an opening through which outside air is admitted, an opening through which inside air is admitted and a discharge opening through which the mixture of the two airs is propelled into the upper stratum in sufficient quantity and

- with sufficient velocity to be available to the humidifying means distributed about the intermediate stratum; and exit means for discharge of air from the inclosure located remote from said air propelling means; the said humidifying means acting to move air from said upper stratum into said intermediate stratum and there to highly humidify and cool the air, whereby said highly humidified and cooled air descends from the intermediate stratum into the lower stratum and reduces the temperature of and establishes the desired condition of relative humidity in the air of said lower stratum, there being a general movement of air throughout the inclosure from said air propelling means to said remote exit means.
3. An evaporative cooling system for an inclosure having a lower stratum of air adjacent to the floor in which a desired relative humidity is to be maintained, humidifying means distributed about the inclosure above said lower stratum and within an intermediate stratum within which latter stratum the relative humidity is in excess of said desired relative humidity; an opening in an outside wall of the enclosure with air moving means adjacent said opening for drawing in outside air and discharging it directly into said upper stratum; and exit means remote from said air moving means so arranged that the air discharged into said upper stratum traverses the extent thereof in a general direction from said air moving means toward said exit means, thereby making available to all the humidifying means the air of said low relative humidity; the said humidifying means acting to draw the air from the upper stratum into said intermediate stratum and there to humidify it in excess of said desired relative humidity whereby the air is materially cooled, whence said excessively humidified and cooled air descends into the lower stratum there to establish the desired condition of relative humidity while reducing the temperature of said lower stratum.
4. An evaporative cooling system for a humidified inclosure in which it is desired to cool the air of a lower stratum adjacent the floor while maintaining the relative humidity of the air in said stratum substantially uniform, which system comprises, in combination, humidifying means distributed about the inclosure and located in an intermediate stratum of air just above the said lower stratum, an inlet opening in an outside wall of said inclosure with means adjacent said inlet opening for drawing in outside air and propelling it directly into an upper stratum of air above said intermediate stratum, and air exit means located in the inclosure remote from said propelling means; the said propelling means being constructed and arranged to effect distribution of said outside air throughout the said upper stratum wherefrom said air is drawn downward into the intermediate stratum by the action of the humidifying means and highly humidified and descends thence into the lower stratum there to accomplish the desired cooling and maintenance of the relative humidity.
5. An evaporative cooling system for a humidified inclosure having a lower stratum in which heat primarily liberated from operating machinery tends to maintain an excessive temperature and in which stratum it is desired to cool the air while maintaining it at a desired condition of relative humidity, which system comprises an inlet opening in an outside wall of the inclosure with means adjacent thereto for drawing in air and propelling it directly into an upper stratum of the inclosure; humidifying means distributed about said inclosure in an intermediate stratum between said upper and lower strata; and air exit means located in said inclosure remote from said propelling means; the said humidifying means acting to cause movement of the air from said upper stratum into said intermediate stratum and there to highly humidify the air and cool it to a temperature materially below that of the lower stratum, whence such highly humidified and cooled air descends into the lower stratum and encounters the liberated heat whereby there is produced the desired condition of relative humidity at a temperature below that which would otherwise be effected by said heat liberation.
6. An evaporative cooling system for a humidified inclosure in which it is desired to cool the air in a lower stratum adjacent the floor while maintaining the relative humidity of the air in said stratum substantially uniform, which system comprises humidifying means distributed about the inclosure and located in an intermediate stratum of air just above the said lower stratum, an inlet opening in an outside wall of said inclosure with means adjacent said inlet opening for effecting a mixture of outside air with air taken from the inclosure, means for propelling said mixture directly into an upper stratum of air above said intermediate stratum, control means responsive to changes of an air condition within the inclosure for regulating the proportion of outside air and inside making up said mixture, and an exit opening from said inclosure remote from said propelling means; the said propelling means and exit opening being constructed and arranged to effect distribution of said drawn-in air throughout the said upper stratum wherefrom said air may pass into the intermediate stratum and be highly humidified and thence descend into the lower stratum to accomplish the desired cooling and maintenance of the relative humidity.
7. An evaporative cooling system for a humidified inclosure in which it is desired to cool the air in a lower stratum adjacent the floor while maintaining the relative humidity of the air in said stratum substantially uniform, which system comprises, in combination, an inlet opening in an outside wall of said inclosure, means adjacent to said opening for drawing in outside air and propelling it directly into an upper stratum of air adjacent the top of said inclosure, a series of humidifying units distributed about the inclosure in an intermediate stratum of air between the said lower and upper strata, and exit means for discharge of air from the inclosure located remote from said inlet opening; the aforesaid propelling means being constructed and arranged to effect a general distribution of the outside air through the said upper stratum, wherefrom the air is drawn downward by the action of the humidifying units into the said intermediate stratum and there highly humidified, whence said highly humidified air passes into the said lower stratum to effect the desired cooling and the maintenance of a substantially uniform relative humidity condition therein, there being a continuous movement of air generally from the inlet opening toward the said remote exit means.

ALBERT J. LOEPSINGER.
